SHAKER FOR A COMMODITY

Solomon Edward Miller, Gary, Ind.

Application November 8, 1952, Serial No. 319,451

9 Claims. (Cl. 222—39)

This invention relates generally to dispensing devices and more particularly to a shaker for a condiment, such as salt or pepper.

The principal object of the invention is to provide a device embodying improved principles of design and construction.

A particular object of the invention is to provide a shaker comprising an outer pistol-like member and an inner pistol-like container member pivotally mounted in the outer member, with an actuator or trigger for actuating the container to dispense a commodity therefrom.

A significant object of the invention is to provide a shaker preferably in the form of a pistol in which the commodity to be dispensed can be dispensed only when the shaker is held in any position within a predetermined range of movement. More specifically in this respect, the arrangement is such that when the shaker is positioned on a support such as a table or counter, manipulation of the trigger will not permit release of the commodity but when the barrel of the shaker is pointed downwardly toward food to be seasoned or flavored, manipulation of the trigger will allow and control the flow of the commodity in quantities desired.

A specific object of the invention is to provide a device simulating a pistol which may be utilized as a toy to produce noise irrespective of its use as a shaker.

A further object of the invention is to provide a device in which the handle of the outer member is comprised of a pair of complementary parts which are constructed and arranged to facilitate assembly of the inner and outer members of the device.

Another object of the invention is to provide a shaker device preferably comprised of moulded plastic corresponding components or elements to facilitate assembly and produce costs of manufacture and at the same time alleviate the problem of corrosion.

Many other objects and advantages of the invention will become apparent after the description hereinafter set forth is considered in conjunction with the drawings annexed hereto.

In the drawings wherein the preferred embodiment of the invention is exemplified:

Figure 1 is a front end elevational view of the shaker device;

Figure 2 is a side elevational view of the device;

Figure 3 is a rear end elevational view thereof;

Figure 4 is a longitudinal sectional view of the outer pistol-like member and showing one position of the container therein;

Figure 5 is a view similar to Figure 4 showing the container in another position;

Figure 6 is a transverse sectional view taken through the device shown in Figure 2; and

Figure 7 is a bottom end view of the handle portion of the device.

Referring to the drawings, numeral 1 generally designates an outer hollow pistol-like member having a barrel 2, a handle 3 and a trigger guard 4. Numeral 5 generally

2

designates an inner hollow pistol-like member having a barrel 6 and a butt 7, respectively arranged in the barrel 2 and handle 3 of the outer member 1. The butt 7 of the inner member serves as a container for a commodity, such as salt, and will be described in detail subsequently.

5 The outer member is preferably moulded from a desirable plastic material and to facilitate its construction and assembly of the inner member therewith, its rear extremity is open. When the inner member is assembled with the outer member, the open rear extremity is permanently closed by a cover 8 seated therein. This cover is complementary to the outer member and forms a part of its rear extremity.

The handle of the outer member is preferably formed 15 with a base 9 of a sufficient size to support the device upright on a table or counter with the barrel 2 in a horizontal position. The base is open so as to afford access to the container 7 of the inner member.

The forward portion of the outer member adjacent the 20 junction between its barrel and handle is provided with an aperture 10 at the rear of the trigger guard 4 and the free end of the barrel 2 is provided with an oblong clearance hole 11 through which the barrel 6 of the inner member extends.

25 The inner member is preferably moulded from plastic and is provided with a trigger 12 formed integrally with the barrel 6 and butt 7 for reinforcing the inner member. This trigger projects forwardly through the aperture 10 in the outer member and a pivot 13 extends through the 30 barrel of the outer member and through the forward portion of the trigger for pivotally connecting the members together. Since the portion of the trigger through which the pivot extends is formed on the barrel 6 it can be said, in one sense, that the barrels of the members are pivotally 35 connected and in another sense that the trigger is pivotally connected to the outer member. The inner member is of a size somewhat less than the size of the outer member so that when the trigger is pressed the inner member will swing on the pivot 12. The shapes of the members are 40 such that the outer member in some measure guides the movement of the inner member as will be evident by reference to Figure 6 of the drawing. The upper extremity of the butt 7 is preferably provided with abutment means 14 which is adapted to strike or bang against the upper portion of the barrel 2 as shown in Figure 5 45 when the trigger is actuated. Obviously abutment means can be formed on some other part of the butt, and if found desirable, abutment means can be provided on the outer member for engaging abutment means on the inner member. The arrangement is preferably such that when the 50 abutment means on the inner member is forcibly struck against the outer member considerable noise will be produced to simulate the firing of a pistol. This movement of the inner member also serves to agitate the commodity and keep it in a loose condition so that it can flow freely 55 through apertures 15, provided in a partition 16 preferably located at the junction between the barrel 6 and butt container 7.

The lower extremity of the container 7 is sealed off by 60 a closure 17 secured in the container and the closure is provided with a refill opening normally closed by a removable plug 18 which is accessible through the open base of the handle 3.

In view of the foregoing description it will be manifest 65 that when the device is supported on a table or in the hand in an upright position or is pointed upwardly, no condiment will be released when the trigger is pressed. In such positions the inner member can be repeatedly actuated to produce a banging noise like the firing of a pistol. However, when the device is pivoted downwardly 70 at an appropriate angle toward food to be seasoned and

the inner member is actuated, the condiment will pass through the apertures and out through the barrel 6.

Having thus described my invention it is to be understood that various modifications may be made in the same without departing from the spirit of the invention as defined in the appended claims.

I claim:

1. A device of the kind described comprising a hollow outer member, a hollow non-collapsible inner container member mounted for movement in the outer member, said inner container member being provided with a passage to permit dispensing of a commodity therefrom, and an actuator carried by one of the members for actuating the inner container member. 10

2. The device defined in claim 1 in which the bottom of the inner container member is provided with a refill aperture and the bottom of the outer member is provided with an entrance opening to permit access to the aperture. 15

3. A device of the kind described comprising a hollow outer member provided with an opening, a hollow rigid container member mounted for movement in the outer member and having a tubular portion disposed in the opening, said container member being formed to permit release of a commodity from the container out through the tubular portion only when the device is tipped so that the tubular portion is pointed downwardly, and an actuator carried by the inner member for actuating the container member. 20

4. A device of the kind described comprising a hollow outer member having a handle and a barrel, said handle having a base wall for supporting the device on a mounting so that the barrel will assume a substantially horizontal position, a hollow rigid inner member mounted for pivotal movement in the inner member and having a container arranged in the handle and a tube arranged in the barrel, said inner member being formed so that a commodity when placed therein may flow into the tube of the inner member from the container only when the tube is pointed downwardly, and an actuator carried by one of the members for actuating the inner member. 30

5. A device of the kind described comprising a hollow rigid outer member having a handle and a tube, said handle having a base wall for supporting the device on a mounting so that the tube will assume a substantially horizontal position, a hollow rigid inner member mounted for pivotal movement in the inner member and having a butt and a rigid tube respectively arranged in the handle and tube of the outer member, abutment means on one of the members, and an actuator carried by one of the members in a manner whereby the inner member may be forcibly moved to produce noise when the abutment means and one of the members are brought into engagement. 50

6. A device of the kind described comprising a hollow rigid outer pistol-like member having a handle and a 55

barrel, a hollow rigid inner pistol-like member having a butt and a barrel respectively arranged in the handle and barrel of the outer member, said inner member being of size somewhat smaller than the outer member to permit movement of the inner member in the outer member, an apertured partition provided in the inner member adjacent the junction between the barrel and butt, and a trigger carried by the inner member for actuating the inner member.

7. A device of the kind described comprising a hollow rigid outer pistol-like member having a handle and a barrel, a hollow rigid inner pistol-like member having a butt and a barrel respectively arranged in the handle and barrel of the outer member, said inner member being of size somewhat smaller than the outer member to permit movement of the inner member in the outer member, and a trigger carried by the inner member cooperable with the inner member for actuating the inner member. 15

8. A device of the kind described comprising a hollow rigid outer pistol-like member having a handle and a barrel, a hollow rigid inner pistol-like member having a butt and a barrel respectively arranged in the handle and barrel of the outer member, said butt constituting a container for a commodity adapted to be dispensed outwardly through the barrel of the inner member, said inner member being of size somewhat smaller than the outer member to permit movement of the inner member in the outer member, and a trigger carried by the inner member for actuating the inner member, the arrangement being such that actuation of the inner member will allow release of a commodity only when the device is held within a predetermined range of movement. 25

9. A device of the kind described comprising a hollow outer member having a barrel portion and a handle portion offset from the barrel portion, a hollow non-collapsible inner member having an elongated portion and an offset container portion respectively disposed in the barrel portion and handle portion of the outer member, the elongated portion of said inner member being provided with a passage communicating with the interior of the container and serving to permit discharge of a commodity from the container, and an actuator carried by one of the members for actuating the inner member. 30
